UNITED STATES PATENT OFFICE.

HARRY B. PULSIFER, OF WORCESTER, MASSACHUSETTS, ASSIGNOR TO THE PULSIFER & LARSON CO., OF WORCESTER, MASSACHUSETTS, A CORPORATION OF MASSACHUSETTS.

ILLUMINATED SIGN.

SPECIFICATION forming part of Letters Patent No. 739,926, dated September 29, 1903.

Application filed June 8, 1903. Serial No. 160,542. (No model.)

To all whom it may concern:

Be it known that I, HARRY B. PULSIFER, a citizen of the United States, residing at Worcester, in the county of Worcester and 5 State of Massachusetts, have invented a new and useful Illuminated Sign, of which the following is a specification.

This invention relates to that class of signs which are lighted by electricity or otherwise 10 to display advertising or other desired reading matter.

The especial objects of this invention are to provide a sign of this character in which the illuminating-orifices are combined with 15 raised letters or characters in such a way that during the day-time the sign will have the appearance of an ordinary business sign and the presence of the illuminating-orifices will not interfere with its legibility and to have the 20 illuminating-perforations punched through the face-plate of the sign in such a way as to more perfectly prevent rain or snow from beating into the inside of the sign-box.

To these ends this invention consists of the 25 illuminated sign and of the combinations of parts therein, as hereinafter described, and more particularly pointed out in the claims at the end of this specification.

In the accompanying drawings, Figure 1 is 30 a front view of a sign constructed according to this invention. Fig. 2 is an enlarged transverse sectional view thereof, and Fig. 3 is a fragmentary detail view showing the way in which the perforations are made in the sign face-plate.

In that class of signs to which this invention relates the electric lamps or other lights are placed in a sign-box behind a perforated sign-plate, so that when the lamps are lighted 35 the reading matter will be shown by reason of the light shining through the small perforations which outline the letters. In this class of illuminated signs plain sheet-metal sign-faces have heretofore ordinarily been employed. The perforations have usually 40 been punched within the outlines of each letter, and the letters have been simply painted directly onto the plain sheet-metal face. The illuminating-perforations in signs 45 of this class as heretofore constructed have

been so prominent as to interfere with the legibility of such signs during the day-time. To overcome this difficulty in a sign constructed according to my invention, I provide the sign-face with raised or fastened-on 55 letters. The illuminating-perforations are punched outside of the outlines of these letters, and the sides of the raised characters or letters are beveled at sharp angles.

In practice I have found that the raised 60 letters or characters will distract attention from the perforations, so that a sign constructed according to my invention during the day-time will have the appearance of an ordinary business sign, the perforations being 65 substantially invisible, but that when the sign is lighted up at night the raised characters will not interfere with the proper illumination of the sign, but, on the contrary, the beveled edges of the characters will afford 70 additional reflecting means for more clearly outlining the letters.

Referring to the drawings and in detail, the body portion or box of a sign constructed according to this invention as herein illustrated comprises a base-strip 10, an inclined top strip 13, an intermediate strip 12, a vertical sheet-metal sign-face 14, and a sheet-metal back piece 11, the inner surface of 75 which is covered with zinc-foil or otherwise 80 silvered to act as a reflector.

The electric lamps or other lights are arranged in the bottom of the box below the perforations. If electric lamps L are to be used, they are preferably arranged horizontally, as shown, and they are supported at such distance from the reflecting-surface 11 that a substantially uniform illumination will be reflected through the illuminating- 85 openings.

In practice I have found that an ordinary incandescent electric lamp when placed in proper relation to a reflecting-surface of substantially the inclination illustrated will give a uniform illumination for a height of about 95 eighteen inches. For signs which are higher than this two or more rows of lights are required.

The raised characters 16, which are secured upon the front face of the sign, are located 100

within the outlines of the illuminating-perforations. The edges of these raised characters are preferably quite sharply beveled or inclined, so that such edges will not prevent light from shining through the illuminating-perforations, but, on the contrary, will act as reflecting-surfaces for more clearly showing the reading matter when the sign is lighted.

The illuminating - perforations, as most 10 clearly illustrated in Fig. 3, instead of being stamped or punched through the sheet-metal sign-face in the ordinary manner, are each formed with a small pressed-in flange or bead, and I consider this a desirable feature of construction, as I have found in practice that by 15 punching the illuminating-holes in this way snow and rain will be more perfectly excluded from the interior of the sign-box.

I am aware that changes may be made in 20 practicing my invention by those who are skilled in the art without departing from the scope thereof as expressed in the claims. I do not wish, therefore, to be limited to the construction I have herein shown and described; but 25

What I do claim, and desire to secure by Letters Patent of the United States, is—

1. As an article of manufacture, an illuminated sign comprising a sign-box, having a light therein, and having a perforated front

face with raised characters located within the spaces outlined by the illuminating-perforations.

2. As an article of manufacture, an illuminated sign comprising a sign-box having a light located therein, and having a perforated sign-face with raised characters located within the spaces outlined by the illuminating-perforations, said raised characters having beveled or inclined edges which act as reflecting-surfaces for the light passing through the illuminating-perforations. 40

3. As an article of manufacture, an illuminated sign comprising a sign-box with a light located therein, and with a perforated sheet-metal sign-face, each perforation of which is provided with a bent-in protecting flange or rim, and raised characters located within the spaces outlined by the illuminating-perforations, said raised characters having inclined 45 or beveled sides which act as reflecting-surfaces for the light passing through the illuminating-perforations. 50

In testimony whereof I have hereunto set my hand in the presence of two subscribing 55 witnesses.

HARRY B. PULSIFER.
